US00D967186S

(12) **United States Design Patent** (10) Patent No.: **US D967,186 S**
(45) Date of Patent: ** *Oct. 18, 2022

(54) **DISPLAY SCREEN OR PORTION THEREOF WITH ICON**

(71) Applicant: **Waymo LLC**, Mountain View, CA (US)

(72) Inventors: **Peter Crandall**, San Jose, CA (US); **Nirmal Patel**, Sunnyvale, CA (US)

(73) Assignee: **Waymo LLC**, Mountain View, CA (US)

(*) Notice: This patent is subject to a terminal disclaimer.

(**) Term: **15 Years**

(21) Appl. No.: **29/803,217**

(22) Filed: **Aug. 11, 2021**

Related U.S. Application Data

(63) Continuation of application No. 29/623,844, filed on Oct. 27, 2017, now abandoned.

CLAIM

The ornamental design for a display screen or portion thereof with icon, as shown and described.

DESCRIPTION

The FIGURE is a front view of the claimed design for a display screen or portion thereof with icon.

The dot-dash broken line showing a display screen or portion thereof is for the purpose of illustrating portions of the article and forms no part of the claimed design.

1 Claim, 1 Drawing Sheet
